UNITED STATES PATENT OFFICE.

OTTO J. KUHLKE, OF AKRON, OHIO.

GOLF BALL AND METHOD FOR THE MANUFACTURE OF THE SAME.

Application filed May 31, 1928. Serial No. 281,845.

The present invention relates to the manufacture of golf balls and particularly to the manufacture of the resilient rubber core.

In the manufacture of the standard golf ball, the center or core of the ball is wound with a thread rubber of high grade rubber, the thread being wound under tension to impart the required life and resilient properties to the ball. The resilient mass of rubber thus obtained is of comparatively short life and due to the method of winding, soon loses its elastic qualities, a result which may be observed in cutting a golf ball, the thread rubber being limp and lifeless.

It is the object of the present invention to devise a new and improved method of winding or overlaying the rubber upon the core so as to secure a better and more lively construction of the ball. This is accomplished by the method illustrated and described, although the details of the method are not essential and may be varied within the scope of the invention.

It is also an object of the invention to devise a machine for the purpose of carrying out the method of building the center of the ball.

The product of the machine and process is a new form of golf ball which constitutes a further aspect of the invention.

Briefly stated, the invention comprises the wrapping or winding of a tube of rubber about the core of the ball, the tube being stretched to secure the proper resiliency of the rubber and the winding taking place about the core in such a way that a spherical center is obtained.

In the drawings,

Figure 1 is a general plan view of an apparatus appropriate for carrying out the method of the invention, the view being a longitudinal section through the winding mechanism and being taken at the commencement of the winding operation;

Figure 2 is a view of the mold or rolling tube showing the means by which the rubber cover is given the preliminary stretch;

Figure 3 is a detail of the head at the commencement of the winding operation;

Figure 4 is a view showing the initiation of the rolling operation;

Figure 5 is a further view showing details of the mechanism;

Figure 6 is a cross-section on the line 6—6 of Figure 3; and

Figure 7 is a section on the line 7—7 of Figure 1.

The apparatus comprises a forming mold or tube 1, which is in the form of a long, tapered or conical chamber, the smaller end being of substantially the same inner diameter as the core 2 of the golf ball and the larger end of substantially the same diameter as the completely wound or wrapped center.

The core is wound with a sheath or tube of thin, high grade rubber 3 which is in normal or unstretched condition as shown, substantially one-fourth of the diameter and length of the tube or sheath before stretching preparatory to the wrapping operation although the percentage of stretch may be varied within wide limits, and which is tapered to substantially the same extent as the mold. The smaller end of the tube is stretched over the core and fastened to the core by being cemented about its edges.

The tube with the ball therein is then placed in the mold and the larger end of the tube is stretched over a cap 5 which is later mounted on a guide for movement to clamp 75 the mouth of the tube against the mold.

Air under pressure is admitted through an inlet pipe 7 to the interior of the cap and to the interior of the tube, the pressure being sufficiently high to stretch the tube outwardly against the wall of the mold and to drive the core to the far end of the mold, thereby giving the required longitudinal stretch. This causes the tube 3 to be stretched equally in all directions. At this stage of the operation the smaller end of the mold is open to permit escape of air in front of the core. The stretched sheath is shown in Figure 1.

In the smaller end of the mold is located the movable plunger 10 which is mounted in the forward end of a push rod or shaft 11 mounted for sliding movement in a stuffing box 12 on the end of the mold. The inner end of the head is cut away upon an oblique plane and is provided with a wear plate 14 on which is mounted the pusher head 15, this head being rotatable upon a center pin 16 and held

against the wear plate by a spring 18 a ball race 20 being interposed between the parts 14 and 15. The aperture 21 about the pin 16 is cut away as shown to permit freedom of 5 movement to the head.

To the pusher 15 are pivoted a plurality of swinging fingers 22 the outer ends of which are provided with rollers 23. Six of these rollers are shown, their function being to engage 10 the core 2 and roll it in the mold. If the core were to be pushed without changing its axis of rotation, the tube would roll up on the ball in a definite zone. It is desirable to change the axis of rotation of the ball constantly 15 during the rolling operation in order to distribute the folds in the jacket evenly about the entire surface of the core. For this reason the plunger is rotated as it is moved through the mold, while the head is non-rotative. 20

To rotate the plunger, the shaft 11 is rotatably mounted in a cross head 25, which is supported on guide rod 26. The cross head is moved by a piston rod 28 movable in a fluid 25 pressure cylinder 30 paralleling the mold and actuated by pressure admitted at the ends of the cylinder through a control valve 32, from a main air tank 34 which also supplies the air for the inlet 7.

30 Supported in the head 25 is a rotatable threaded shaft 36 which is engaged by a pin 37 on the mold. The shaft 36 is geared to the shaft 11 through gearing 38. It will thus be seen that as the carrier 25 advances, rotation 35 will be imparted to the shaft 11 from the threaded shaft 36 and intermeshing gearing. This will tend to rotate the head. Due to the angular setting of the head the rotation of the plunger 10 will rock the plate and thus 40 advance the rollers 23 into contact with the core in succession around the interior of the chamber. This will apply a continuous force to the core in a spiral path and the direction of rotation of the core will be constantly 45 changed as a result thereof.

During the wrapping or rolling process it is necessary to keep the envelope or tube of 50 rubber at a constant degree of expansion or tension. It may be desirable to equalize the pressures upon opposite sides of the core which can be done through a connecting pipe 40. The pressure in the supply tank is maintained uniform through any suitable accumulator.

55 It will be seen that when the ball is forced to the larger end of the mold it will have built up thereon a multiple series of crossing folds or flutes of rubber under a uniform tension which gives the required elasticity to 60 the golf ball center. With the tubular jacket or sheath there are no exposed edges of rubber as encountered in the usual thread rubber winding, and the rubber sheath, therefore, cannot fray or break down at the edges which 65 is the cause of the thread rubber losing its

elasticity and its life and resiliency. After the winding operation is completed the cap 5 is removed and the wound ball discharged from the mold. It is then covered and completed in any well known or accepted manner. 70 The invention may be applied to other playing balls or wherever a highly resilient spherical object is required.

What is claimed is:

1. A ball construction comprising a core, 75 and a sheath of rubber wrapped thereon, said sheath being formed of a tube of rubber in stretched condition wound in a multiplicity of overlapping and crossing folds.

2. A ball construction comprising a core, 80 and a sheath of rubber wrapped about the core, said sheath being composed of a single tubular envelope of thin rubber in stretched condition and folded upon itself in a plurality of overlapping folds which extend around the 85 core in a multiplicity of planes.

3. A method of manufacturing balls, comprising forming a tube of rubber, inserting a core therein, stretching the tube, and rolling the ball up into the tube to form the tube in 90 a plurality of folds over the core.

4. A method of manufacturing balls, comprising forming a tube of rubber, inserting a core therein, stretching the tube both longitudinally and transversely, and rolling the 95 ball up into the tube to form the tube in a plurality of folds over the core.

5. A method of manufacturing balls, comprising forming a tube of rubber, inserting a core therein, stretching the tube both longitudinally and transversely, and rolling the ball up into the tube to form the tube in a 100 plurality of folds over the core, said rolling operation being performed while the tube is in stretched condition.

105 6. A method of manufacturing balls comprising forming a tube of rubber, inserting a core therein, rolling the core within the tube, and changing the direction of rotation of the core during the rolling operation.

110 7. A method of manufacturing balls comprising attaching a core within one end of a tube of rubber, the tube being normally of smaller diameter than the core, stretching the tube to a diameter larger than the core, and 115 rolling the core inwardly in the tube.

8. A method of manufacturing balls comprising attaching a core within one end of a tube of rubber, stretching the tube to conical form, and rolling the ball inwardly of the 120 tube while maintaining the tube in stretched condition.

9. A method of manufacturing balls comprising attaching a core within one end of a tube of rubber, stretching the tube to conical 125 form, rolling the ball inwardly of the tube while maintaining the tube in stretched condition, and changing the direction of rotation of the core during the rolling operation.

10. A method of manufacturing balls com- 130

prising forming a tube of rubber conical in form, cementing a core to the interior of the tube at its smaller end, expanding the tube both longitudinally and transversely, and 5 rolling the core into the tube.

11. A method of manufacturing balls comprising forming a tube of rubber conical in form, cementing a core to the interior of the

tube at its smaller end, expanding the tube both longitudinally and transversely, and 10 rolling the core into the tube by pushing the core into the tube, the point of application of the force to the core changing about the outer surface of the core.

OTTO J. KUHLKE.
